UNITED STATES PATENT OFFICE.

EMIL M. KEHR, OF WATERTOWN, WISCONSIN.

ELEVATED CARRIER.

No. 839,391.

Specification of Letters Patent.

Patented Dec. 25, 1906.

Application filed March 8, 1906. Serial No. 304,842.

To all whom it may concern:

Be it known that I, EMIL M. KEHR, a citizen of the United States, and a resident of Watertown, in the county of Jefferson and State of Wisconsin, have invented certain new and useful Improvements in Elevated Carriers; and I do hereby declare that the following is a full, clear, and exact description thereof.

My invention consists in certain peculiarities of construction and combination of parts herein shown, described, and claimed, its object being to provide simple economical elevated carriers, each having vertically-adjustable dump-box hangers that are virtually movable sections of a bail constituting part of a traveler and rigid with the same in adjusted position, the relative arrangement of parts being such as to provide against interference of the dump-box latch with the tilt of said box when said latch is retracted from its keeper.

A further object of my invention is to provide for simultaneous adjustment of a latch-pull device and dump-box, as well as to insure automatic predetermined trip of the latch.

The accompanying drawing represents a perspective view of an elevated carrier in accordance with my invention suspended from a track provided with an obstruction in the path of a vertically-reciprocal device constituting part of the latch-trip mechanism of the carrier, parts of said carrier being broken away and in section.

Referring by letter to the drawing, A indicates an overhead track for the traveler of my improved elevated carrier, this track being provided with a depending stationary cam *b* in the path of a tripper *B*, constituting part of a latch-actuating mechanism hereinafter more particularly described. Supported on the track is a traveler comprising a pair of trolley-wheels *C*, a housing *D*, in which the wheels are hung, a beam *E*, bolted to depending branches *c* of the housing, and a bail *F*, held by clips *d* on the beam, these clips being riveted or otherwise rigidly secured to said beam. The ends of the beam are notched for the engagement of the bail that is thus prevented from swaying, and clamping-nuts *e* are run on stay-bolts *f*, run through said beam adjacent to the end notches of same. Opposite its branches the housing *D* of the traveler is provided with depending guard projections *g*, that with said branches

serve to prevent said traveler from jumping the track.

Each end of the bail *F* is provided with a collar *h*, that has sliding fit in tubular hangers *G*, and said bail is in similar engagement with detachable heads *i* of the hangers, these heads being in screw-threaded connection with said hangers. The horizontal tubular lower end *j* of each hanger serves as a bearing for a trunnion *k* of the dump-box *H* of the carrier.

Held by set-screws *m* in vertically-adjusted position on the dump-box hangers are collar-brackets *I*, to which the lower ends of cables *J* are fastened, and the other ends of these cables are fastened to a drum *K*, suspended in hangers *L*, attached to the beam *E* of the traveler central of the same, said cables being trained on rollers *M*, suspended in hanger extensions of the clips *d* aforesaid. Fast on a journal of the drum is a crank *N* and a ratchet-wheel *O*, a detent *n* being hung in connection with one of the hangers *L* to engage with said wheel, the whole constituting a winch.

One of the brackets *I* is provided with a guide extension *p* for the vertical shank of a latch *P*, and another collar-bracket *I'*, held by a set-screw *m'* in adjusted position on the adjacent dump-box hanger, is also provided with a guide extension *p'* for said shank of the latch.

A cord, flexible wire, or cable *Q*, in connection with the upper end of the latch-shank, is trained on one of the rollers *M* and connected to the drum *K* to wind thereon or unwind therefrom with the cables *J*, and the horizontal foot *q* of the latch is engageable with a keeper *r*, attached to the adjacent end of the dump-box. The latch-pull device *Q* runs through an end eye of an angular foot *s* of the tripper *B*, that has a horizontal offset head *t* and is provided with vertical slots engaged by guide-lugs *u*, extending from arms *v* of one of the depending branches *c* of the housing *D* aforesaid. A weighted lever *R* is fulcrumed in connection with the beam *E* of the traveler and connected to the tripper *B* to automatically return the same to normal position after being depressed by a contact of its head *t* with the cam *b*, that depends from the track *A*, above specified.

From the foregoing it will be understood that the vertical adjustment of the dump-box is effected by means of the winch above

specified, and the latch-pull device is kept taut by the same means. The hangers for the dump-box being virtually adjustable sections of the bail of the traveler, they are very rigid in adjusted position, and there being no spring, interference of the latch with the automatic tilt of said box is avoided. The traveler, with a loaded dump-box, being run out on the track, the contact of the tripper with the depending cam of said track will result in a bend of the latch-pull device and a disengagement of the latch from its keeper, whereupon said dump-box is free to tilt. The weighted lever operates to return the latch-pull device and latch to normal position, and the dump-box being swung into like position there is automatic engagement of said latch with its keeper.

I claim—

20 1. An elevated-carrier traveler comprising a bail having end collars, tubular dump-box hangers fitting the collars, and bail-engaging heads on the hangers.

25 2. An elevated-carrier traveler comprising a bail having end collars, tubular dump-box hangers having sliding fit on the collars, bail-engaging heads on the hangers, and means for lifting the hangers on said bail and holding the same in adjusted position.

30 3. An elevated-carrier traveler comprising a bail, rollers and winch; dump-box hangers in telescopic engagement with the bail, cables trained on the rollers and connecting the drum of the winch with brackets of said hangers, a dump-box latch, a flexible pull device for the latch trained on one of said rollers and connected to the winch-drum, a detent arranged to engage a ratchet-wheel in connection with said drum, a tripper in connection with the traveler and latch-pull de-

vice, and a tripper-actuating device in connection with the track for said traveler.

4. An elevated-carrier traveler comprising a beam notched at its ends and a bail in connection with the beam to engage the end notches thereof; dump-box hangers constituting continuations of the bail, a dump-box latch, guides for the latch in connection with one of said hangers, a flexible latch-pull device, a tripper in connection with the traveler and latch-pull device, and a tripper-actuating device in connection with the track for said traveler.

5. An elevated-carrier traveler comprising a beam, a bail on the same and a winch and 55 rollers suspended therefrom; dump-box hangers in telescopic engagement with the bail, cables trained on the rollers and connecting the drum of the winch with brackets of said hangers, a dump-box sliding latch and 60 guides for the same, a flexible pull device trained on one of said rollers and connected to the winch-drum, a detent arranged to engage a ratchet-wheel in connection with said drum, a tripper having vertically-reciprocal 65 connection with the traveler and connected to the latch-pull device, a weighted lever connected to the tripper and fulcrumed in connection with the traveler-beam, and a tripper-actuating device in connection with 70 the track for said traveler.

In testimony that I claim the foregoing I have hereunto set my hand, at Watertown, in the county of Jefferson and State of Wisconsin, in the presence of two witnesses.

EMIL M. KEHR.
